UNITED STATES PATENT OFFICE.

WILLIAM A. FARLEY, OF SEATTLE, WASHINGTON.

SLIDE-BEARING.

1,175,416.

Specification of Letters Patent. Patented Mar. 14, 1916.

Application filed April 1, 1915. Serial No. 18,579.

To all whom it may concern:

Be it known that I, WILLIAM A. FARLEY, a citizen of the United States of America, and a resident of the city of Seattle, in the county of King and State of Washington, have invented certain new and useful Improvements in Slide-Bearings, of which the following is a specification.

My invention relates to slide bearings, and I have shown my device as employed upon a shingle machine of that type which are known to the trade as "upright machines," the same employing a machine frame upon which is mounted for horizontal reciprocation, a shingle-block-carrying frame so as to be capable of horizontal reciprocation toward and from the cutting saw.

My invention comprises certain improvements in the construction of the parts by which the shingle-block-carrying frame is mounted for reciprocation upon the machine frame, whereby the joint between the two frames may be maintained with less slack, the wear may be taken up and such wear as occurs may be quickly and easily repaired.

The novel features of my invention will be hereinafter described in the specification and particularly defined in the claims terminating this specification.

In the accompanying drawings I have shown my invention in the form of construction which is now preferred by me.

Figure 1 is a side elevation of one end of the machine frame showing the shingle-block-carrying frame thereon. Fig. 2 is a top plan view of the slipper or plate which is placed between one side of the shingle-block-carrying frame and the guide of the main frame for this same side. Fig. 3 is a side elevation of the same part with one end in section. Fig. 4 is a section on the line 4—4 of Fig. 1. Fig. 5 is a section on the line 5—5 of Fig. 1.

The type of machine upon which I have shown my invention as placed is that shown in patent to Burpee, No. 864,750 of Aug. 27, 1907. As the general type of this machine is well known, I have herein shown only the parts thereof which are directly related to my invention.

The frame 1 has an upper guide bar 10 and a lower guide bar 11 between which and guided upon which bars is placed the

shingle-block-carrying frame 2. These parts are of the same construction and operate in a manner identical with that shown and described in said patent, except as herein-after stated. The lower bar 20 of this reciprocating frame 2, does not, in my invention make direct contact with the guide bar 11 but has a slipper plate 3 interposed between them. The guide bar 11, as herein shown, is of square cross section having a corner placed upwardly and employs the two sides adjacent to this corner as the frame guiding surfaces. It is evident that the cross sectional shape of this guide is however, not a material feature. Between the slipper 3 and the bar 11 a layer 30 of bearing material, such for instance, as babbitt, may be inserted. The slipper 3 as herein shown has an upwardly projecting bar or tongue 31 which enters a corresponding recess 21 in the frame 2. Two or more of these tongues 31 are preferably employed upon each slipper.

I have herein shown the tongues or guide bars 31, as provided with a T-shaped slot 32 extending from their upper end surface downwardly. These are intended for the reception of a T-shaped head 40 of a bolt 4, which bolt passes through a flange 22 which forms a part of the shingle-block-carrying frame 2. When the slipper 3 has been adjusted so as to take up all slack, it may be secured in this adjusted position by tightening the clamping bolts 4. Adjusting bolts 41 are threaded through the upper part of the bar 20 of said frame, and bear upon the upper end surface of the tongue or guide bar 31. By this or similar means accurate adjustment may be obtained.

In the construction of the machines as shown in the Burpee patent referred to, wheels are shown between the frame 2 and the bar 11. With this type of construction it is practically impossible to prevent the occurrence of a certain amount of slack. As a result of this the presentation of the block to the saw is likely to vary causing the tips of the shingles particularly to be either too thick or too thin, this sometimes resulting in what is known as "feather tipped" shingles, that is, the tip is reduced in places to nothing and this makes an irregular, ragged edge.

The construction herein shown and described makes it possible to maintain a tight

bearing and to thus eliminate all slack, this resulting in the production of shingles of uniform dimensions and character.

I prefer to omit the Babbitt lining 30, for a distance at the center of the slipper, replacing this with felt 33, which acts as a reservoir of lubricating oil.

Having thus described my invention what I claim as new, and desire to secure by Letters Patent of the United States of America, is:

1. In a device of the character described, in combination, a stationary frame, a frame sliding thereon and having reciprocative guiding engagement with the stationary frame, one of the guide bearings between said frames containing a slipper having a guide stem extending in the plane of the sliding frame, this frame having a guiding socket for the reception of said stem, and means for adjusting and holding said stem in a direction which is normal to the direction of reciprocation.

2. In a device of the character described, in combination, a stationary frame having guides for the sliding frame, said sliding frame having guiding engagement with said guides, a slipper interposed between the

sliding frame and a guide and having guide stems extending toward the opposite bearing, the sliding frame having sockets for the reception of said stems and means for adjusting said slipper toward its bearing member.

3. In a device of the character described, in combination, a stationary frame, a frame sliding thereon and having reciprocative guiding engagement with the stationary frame, one of the guide bearings between said frames containing a slipper having a guide stem extending in the plane of the sliding frame, this frame having a guiding socket for the reception of said stem, means for adjusting said stem in a direction which is normal to the direction of reciprocation, a slot in said stem extending toward the sliding member, and a bolt slidable in said slot and adapted to be secured in said socket in the sliding frame to hold said stem in adjusted position.

Signed at Seattle, Washington, this 27th day of March, 1915.

WILLIAM A. FARLEY.
